UNITED STATES PATENT OFFICE

169,025

HANDBAG WITH REMOVABLE COVER

George Arden, New York, N. Y.

Application April 9, 1952, Serial No. 19,262

Term of patent 14 years

(Cl. D87—3)

To all whom it may concern:

Be it known that I, George Arden, a citizen of the United States and a resident of the city, county, and State of New York, have invented a new, original, and ornamental Design for a Handbag With Removable Cover, of which the following is a specification, reference being had to the accompanying drawing, forming a part thereof, wherein:

Fig. 1 is a side elevational view of a handbag with removable cover, embodying my new design, the handbag being shown in closed condition;

Fig. 2 is a plan view, with the handbag shown in open condition;

Fig. 3 is a similar view, but with the foundation bag lifted from the cover;

Fig. 4 is a side elevational view similar to Fig. 1, but with the cover shown in reversed condition; and

Fig. 5 is a perspective view of the foundation handbag, with the cover removed, and with the bag in open condition.

One side of the reversible cover is shown darkly

shaded in Figs. 1, 2 and 3 in order to indicate contrast with its opposite side, which is shown at the inside in Fig. 3, and at the outside in Fig. 4.

I claim:

The ornamental design for a handbag with removable cover, substantially as shown and described.

GEORGE ARDEN.
